US00D664456S

(12) **United States Design Patent**
Trine et al.

(10) **Patent No.:** US D664,456 S
(45) **Date of Patent:** ** Jul. 31, 2012

(54) **OCCUPANCY SENSOR**

(75) Inventors: **David R. Trine**, Portland, OR (US); **Joel Van Faasen**, Holland, MI (US)

(73) Assignee: **Leviton Manufacturing Co., Inc.**, Melville, NY (US)

(**) Term: **14 Years**

(21) Appl. No.: **29/402,087**

(22) Filed: **Sep. 20, 2011**

(57) **CLAIM**

The ornamental design for an occupancy sensor, as shown and described.

DESCRIPTION

A portion of the disclosure of this patent document contains material which is subject to copyright protection. The copyright owner has no objection to the facsimile reproduction by anyone of the patent disclosure, as it appears in the Patent and Trademark Office patent files or records, but otherwise reserves all copyright rights whatsoever.

FIG. 1 is a perspective view of an design for an occupancy sensor;

FIG. 2 is a left side elevation view thereof;

FIG. 3 is a front elevation view thereof; and,

FIG. 4 is a top plan view thereof.

The dashed lines in the figures illustrate environment only and form no part of the claimed design.
